Patented July 18, 1922.

UNITED STATES PATENT OFFICE.

ELDRIDGE H. NOBLE, OF WAUKEGAN, ILLINOIS; WILLIAM J. SMITH ADMINISTRATOR
OF SAID ELDREDGE H. NOBLE, DECEASED.

OIL CAN.

1,423,503.

Specification of Letters Patent. Patented July 18, 1923.

Application filed November 17, 1919. Serial No. 338,376.

To all whom it may concern:

Be it known that I, ELDREDGE H. NOBLE, citizen of the United States, residing at Waukegan, in the county of Lake and State 5 of Illinois, have invented a certain new and useful Improvement in Oil Cans, of which the following is a full, clear, concise, and exact description.

My invention relates to spouted cans commonly used for squirting or otherwise discharging oil or other material.

My invention has for its main object the construction of such a can which, with one operation of the finger, will unstop the 15 spout thereof, throw the oil, and restore the stop to the spout. A stopper for the spout is preferably of such a construction as to normally seal the outlet end thereof to make it impossible for the spout to be clogged by 20 dirt or other foreign substance.

The invention will be fully explained by the following description of the preferred embodiment thereof shown in the accompanying drawing in which Fig. 1 is a vertical sectional view of the can of my invention with the spout thereof "corked"; Fig. 2 illustrates the can uncorked to permit of the passage of oil therefrom; and Fig. 3 is a sectional view on line 3—3 of Fig. 1.

Like parts are indicated by similar characters of reference throughout the different figures.

The body 1 of the oil can is of any suitable shell-like form. It is provided at its 35 upper end with a neck 2 formed to have separable connection with the base of the skirt of a cap 3. The top wall 4 of the cap is in assembly with the base portion of the discharge spout 5 through which the oil is 40 to be ejected. The top cap portion 4 constitutes the bottom of a cup 6 which surrounds the base of the spout 5 to retain any oil that may flow down along the spout thereby preventing the oil from reaching the 45 base portion of the can and thence flowing to the table or other support upon which the can may be rested. An elongated stopper 7 is reciprocable within the bore of the spout. The stopper is wire-like in formation, being tapered at its outer end to seal the discharge end of the spout when the can is not in use. The stopper is provided with an enlargement 8 to engage the shoulder 9 formed within the spout, when the can is

not in use, whereby a supplemental sealing 55 of the spout is afforded. There is clearance between the bore of the spout and the stopper therein except at the outer end of the spout and stopper and between the stopper enlargement 8 and the spout, when the can 60 is not in use, so that when the spout is to be unstopped the stopper may readily be drawn inwardly without being materially opposed in its movement by any friction between the spout and stopper. A plunger 10, 65 preferably parallel with the spout, is preferably employed to operate the stopper 7. This plunger extends from the exterior of the can through the stuffing box 11 and the cap top 4 to the interior of the can where 70 it is securely connected with a spring barrel 12 which is also a pump barrel. A pump piston 13 is disposed within the pump barrel, being preferably made stationary with respect to the can by means of a link 14 75 that connects it with the spout 5. This pump piston also constitutes the lower or inner abutment for a coiled spring 15 having as its upper or outer abutment the outer end wall of the pump barrel 12. The spring 80 15 normally holds the pump barrel in its outermost position in which the stopper enlargement 8 and the tapered end of the stopper 7 serve doubly to seal the spout to prevent oil from passing from the can in any 85 position in which the can may be placed.

The pump barrel is provided with openings or ports 16 at its inner end which extend outwardly above the pump piston when the pump barrel is in its outermost position whereby oil from the can may readily flow into the pump barrel to be forcibly ejected therefrom when the plunger 10 is depressed to move the outer end of the pump barrel toward the piston and at the same 90 time unstopp the spout. The finger which is employed to depress the plunger is removed as soon as the pump barrel is sufficiently moved inwardly to squirt the desired amount of oil from the spout, the spring 15 thereupon restoring the pump barrel to its outer position. By this construction the forcible application of the finger to the plunger will unstopp the spout and effect the forced passage of oil therethrough, the release of the 95 finger from the plunger permitting the spring 15 to restore the pump barrel to its idle position and apply the stopper to the 100 105

spout to avoid the clogging of the spout. The stopper projects beyond the spout to be used to clean out oil holes.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. A can having a discharge spout; a stopper within the bore of the spout; mechanism accessible for operation upon the exterior of the can and in operating connection with the stopper upon the interior of the can; a pump barrel to which the stopper is attached and moving with the stopper, the aforesaid mechanism being in actuating relation to this pump barrel; a piston within the pump barrel and substantially fixed with respect to the can; and a spring between the piston and the outer end of the pump barrel normally to place the pump barrel in its outer position and to apply the stopper to

the spout, there being communication between the pump barrel and the can interior when the pump barrel is in its outer position.

2. A can having a discharge spout; a stopper within the bore of the spout; a pump barrel to which the stopper is attached and moving with the stopper; a piston within the pump barrel and substantially fixed with respect to the can; a spring between the piston and the outer end of the pump barrel normally to place the pump barrel in its outer position and to apply the stopper to the spout, there being communication between the pump barrel and the can interior when the pump barrel is in its outer position; and a plunger extending through the can to the exterior thereof and connected with the pump barrel to move it inwardly and thereby unstop the spout and effect the forcible passage therethrough of material from the can.

In witness whereof, I hereunto subscribe my name this eleventh day of November, A. D. 1917.

ELDRIDGE H. NOBLE.
